UNITED STATES PATENT OFFICE.

WILLIAM L. NORTON, OF KANSAS CITY, MISSOURI.

UNDERGARMENT.

1,146,092.

Specification of Letters Patent. Patented July 13, 1915.

Application filed June 19, 1914. Serial No. 846,177.

To all whom it may concern:

Be it known that I, WILLIAM L. NORTON, a citizen of the United States, residing at Kansas City, in the county of Jackson and 5 State of Missouri, have invented certain new and useful Improvements in Undergarments; and I do declare the following to be a full, clear, and exact description of the invention, such as will enable others skilled 10 in the art to which it appertains to make and use the same.

The present invention relates to wearing apparel and more particularly to undergarments, the particular object in view being 15 to provide a more comfortable undergarment of the athletic or knee-length type.

To this end the invention resides in providing the knee portions of knee-length undergarments with a suitable extension 20 whereby the rubbing, chafing or binding, or otherwise objectionable features, which are frequently experienced by the wearers of such garments, are in a great measure eliminated.

Having the above-stated general object in view, the invention will now be described 25 by reference to several forms of embodiment thereof, as illustrated by the accompanying drawing, after which the particular features 30 deemed to be novel will be severally specified in the appended claim.

In the drawing—Figure 1 is a rear plan view of an athletic undergarment embodying one form of the improvements forming 35 the subject matter of the present invention; Fig. 2 is a side elevation illustrating the garment in use; Fig. 3 is a fragmentary plan view, showing a side view of one of the knee portions of the garment with an extension thereto of the same form as illustrated in Figs. 1 and 2; Fig. 4 is a fragmentary plan view of one of the knee portions of the garment with a modified form 40 of extension; and Fig. 5 is a fragmentary 45 perspective view of one of said knee portions with a further modified form of extension.

Referring to the drawing, an undergarment is illustrated having a body portion 2, 50 which may be of any of the common forms now in general use, having the leg portions 4 of approximately knee-length. In the present invention, however, these leg portions are provided with flaps or apron-like 55 extensions which will be adapted to overlie the knee of the wearer on taking a sitting

posture as illustrated in Fig. 2, and likewise be adapted to constantly overlie or embrace the knee without binding in any other than standing position of the wearer. In the 60 form of flap or extension disclosed in Figs. 1, 2 and 3, the same comprises an apron 6 secured by stitching 8 to the lower edge of the knee portion 4. This apron is of such 65 length as to continue to overlie the knee of the wearer at all times, regardless of the wearer's position, and is of such width as to leave its rear edges spaced apart, forming a gap 10 to facilitate the free movement of the knee joint without any binding of the 70 apron.

In Fig. 4 the flap or apron is formed as simply a continuation of the goods or material comprising the leg portion of the garment without the use of any stitching 8 as 75 in the first form of apron; but the rear edges of this modified form are spaced apart to provide the same character of gap 10 for the purposes above stated.

In Fig. 5, the leg portion 4 is provided with 80 the continuous apron extension 6, and the gap 10 is formed by simply slitting the extension, as illustrated, which slit may, obviously, be either at the rear or at the side of the garment and still afford the necessary 85 freedom of movement of the knee joint; but it is preferred to locate the slit always at the rear so as to make certain that the extension will have no tendency to work away 90 sidewise from the points around the knee. 90

In the usual athletic undergarment having the knee-length leg portions, the lower edges of the leg portions tend, in other than standing positions of the wearer, to shift to a position somewhat above the knee, as illustrated by the seam of stitching 8 in Fig. 2. This exposes the knee to rubbing contact with the outer garment, which is frequently 100 of a material calculated to chafe and irritate such rubbed portions, to the wearer's 105 great discomfort. To avoid this it has become more or less common to sew a patch of lining of silk or similar material to the interior of the outer garment at the knees, which practice is objectionable because making it more difficult to make the outer garment hold its shape. If the wearer seeks to 110 overcome the chafing objection by adopting a garment with longer leg portions, he still is troubled with binding of the knee portions about his knees, when not standing, since the knee extensions are continuous 115

about the knee joints; moreover, since such knee-extensions completely inclose the knee joints, they are more or less close-fitting when the wearer is sitting, and consequently 5 not so cool or otherwise so comfortable as a loose-fitting extension such as provided by this invention. It will thus be apparent that the object of the invention is simply and effectively accomplished by providing an 10 apron extension open at one side or the rear thereof to afford full freedom to the knee joints by eliminating any binding about the joints and completely protecting the knees at all times from any rubbing or chafing 15 contact with the outer garment.

While the forms of the invention herein illustrated are what have been found to be satisfactory forms of embodiment of the

same, the right is reserved to such changes or modifications as may fairly fall within 20 the scope of the following claim.

Claim:

In an undergarment, a body portion having leg portions of approximately knee-length, and extensions to said leg portions 25 for extending below the knee, the rear portion of each extension having a gap therein extending from its lower edge to the lower end of the corresponding leg portion.

In testimony whereof I affix my signature 30 in the presence of two witnesses.

WILLIAM L. NORTON.
